UNITED STATES PATENT OFFICE.

FRANK A. MAGEE, OF BOSTON, MASSACHUSETTS.

DESIGN FOR A STOVE.

SPECIFICATION forming part of Design No. 21,713, dated July 12, 1892.

Application filed June 10, 1892. Serial No. 436,283. Term of patent 14 years.

To all whom it may concern:

Be it known that I, FRANK A. MAGEE, of Boston, in the county of Suffolk and State of Massachusetts, have invented and produced 5 a new and original Design for Stoves, of which the following is a specification, reference being had to the accompanying photographic illustration, showing the essential features thereof.

10 The drawing represents a perspective view of the major portion of a stove, illustrating my design, the portion shown not completed being merely a complementary repetition of the completed portion shown.

15 My design is for an open grate having a swell front rising from the hearth and terminating in a fluted hood A at the top. The hearth B is semi-oval, having a molding edge. The legs C are fluted and have claws inclosing a ball. The draft-door D has a series of 20 segmental oblong openings with ribbon ornaments intervening. The fire-pot front P has a central rosette with radiating flames each side extending horizontally outward and a bead-molding F at the bottom next the draft-door and a similar beaded molding T at the

base or lower edge of the hood A. The sliding doors G have ornamental raised panels with festooned leaf ornaments and ribbons. An ornamental scroll-panel H surrounds the 30 top of the hood A, extending downward at the opposite ends, as shown. The fluted pillars K extend from the hearth to the top, with rosettes near top and bottom and at center. The top L has a wide fluted molding R, with 35 leaf corners and a central urn. From opposite sides of the front, projecting forward and curved outward, are wing-pieces M, broad at the hearth and tapering irregularly to the top.

Having thus described my design, I claim— 40

The design for an open-grate stove herein shown and described, the same comprising the fluted hood A, the semi-oval hearth B, fluted legs C, having claws inclosing a ball, the draft-door D, fire-pot front P, bead-moldings F and 45 T, sliding doors G, scroll-panel H, the fluted pillars K, the top L, having a wide fluted molding R, and wing-pieces M, as set forth.

FRANK A. MAGEE.
